UNITED STATES PATENT OFFICE.

ENOCH OHNSTRAND, OF MOHAWK, NEW YORK, ASSIGNOR TO LIBRARY BUREAU, OF
CAMBRIDGE, MASSACHUSETTS, A CORPORATION OF NEW JERSEY.

LATCH.

1,407,884.

Specification of Letters Patent. Patented Feb. 28, 1922.

Application filed August 11, 1920. Serial No. 402,782.

To all whom it may concern:

Be it known that I, ENOCH OHNSTRAND, citizen of the United States, and resident of Mohawk, in the county of Herkimer and 5 State of New York, have invented new and useful Improvements in Latches, of which the following is a specification.

This invention relates to a new and improved drawer pull and latch and more specifically to device of this character in which the latch is operated by the movement of the pull handle.

In the use of drawers in desks or filing cabinets or in connection with cabinet or 15 other closures of similar types it is often desirable to provide means for latching the closure or drawer in place. This is particularly true in the case of drawers which are adapted to be drawn outward endwise in 20 either direction from a file stack or desk pedestal. In closing such drawers there is a tendency for the drawer, due to its inertia and the momentum acquired during the closing movement, to pass beyond its central or 25 closed position and to extend outward upon the opposite side of the stack or pedestal.

The latch to be of utility in such construction must permit the drawer to be drawn outward from the opposite end than that occupied by the latch. The latch should be 30 capable of use in pairs, one upon each end of the double extending drawer and the use of the latch upon the end toward which the drawer is to be moved should be sufficient to 35 release the drawer for movement.

It is an object of my invention to provide a combined latch and pull of the character described which is automatic in its action in that the latch is released by the normal actuation of the pull handle. It is also an object to provide a device which is simple in construction, which comprises but few parts and which is relatively inexpensive to manufacture. Other and further objects will 45 appear as the description proceeds.

I have illustrated a preferred embodiment of my invention in the accompanying drawing in which;

Figure 1 is a front view of the device,
50 Figure 2 is a view of Fig. 1 as seen from the right,
Figure 3 is a section on line 3—3 of Fig. 1,
Figure 4 is a section in line 4—4 of Fig. 1, and
55 Figure 5 is a fragmentary face view of the back member.

The latch comprises the back member 6, the face member 7, pull handle 8, rock shaft 9 and bolt 10. The back member 6 and face member 7 are secured together and to the 60 drawer face 11 by the bolts 12. The member 6 is preferably formed of a sheet metal stamping and has the side members 13 struck up and bent forward, their forward faces being concave to receive the rear face of the 65 pull handle 8. The face member 7 is bent outwardly to house the latch mechanism and is cut away at the sides to permit introduction of the pull handle 8 and the members 13 on the back member 6. 70

The pull handle 8 is a solid loop of metal substantially circular in cross section as shown. At the point 14 inside the face member the pull handle is cut away and the remaining portion extended oppositely somewhat at 15. The rock shaft 9 is carried by the pin 16, the ends of the latter being upset to retain it in place in the face member. The rock shaft 9 is provided with the cam lug 17 adapted to coact with the adjacent portion of 80 the pull handle and is also provided with the lift finger 18 adapted to lift the bolt. 75

The bolt 10 is cut away at 19 to receive the lift finger 18. The bottom end of the bolt is rearwardly beveled at 20. 85

The catch 21 is attached to the fixed portion 22 of the desk or cabinet by the bolts 23. This catch engages the bolt 10 as shown in Figs. 1 and 2.

The latch may be readily assembled or 90 dismantled, removal of the bolts 12 permitting the face member to be disengaged from the back member and the bolt and pull handle may then both be removed.

As shown in Figs. 1 and 2 the engagement 95 of the bolt 10 with the catch 21 effectually maintains the drawer closed. Pulling upon the pull handle 8 in opening the drawer swings that handle to the position shown in Fig. 3, the engagement between the cam 100 portion of the handle and the cam lug 17 on the rock shaft serving to rotate that shaft sufficiently to cause the lift finger 18 to lift the bolt out of engagement with the catch 21. In closing the drawer the beveled surface 20 on the bolt 10 engages the lip of the catch 21 and serves to lift the bolt over the catch. The cut away portion 19 of the bolt is of sufficient height to permit this lift of 110 the bolt without causing any movement of the rock shaft or pull handle.

In the use of this type of latch with a

drawer of the type adapted to be drawn out in either direction, a pair of latches will be attached, one upon each end of the drawer. The latch upon the end of the drawer which 5 is to be drawn outward will operate in the manner which has been described. The bolt of the latch upon the opposite end will be lifted by means of its beveled cam surface 10 which will ride up over the fixed portion 20 of the desk or cabinet, the portion 19 of the bolt permitting the handle to remain stationary. When the drawer is again 15 closed the bolt of this latch upon the opposite end will drop into its catch and it will be impossible to push the drawer in beyond its central or normal position. It will be possible to pull the drawer out in either direction by pulling upon the corresponding latch but if the drawer is closed simply by 20 giving it a push the opposite latch will positively stop it at the proper point.

I claim:

1. A drawer latch device comprising a sheet metal casing having aligned openings 25 in its opposite walls, a loop handle having a portion of substantially circular cross-section journaled in said openings, said handle having an offset cam portion intermediate 30 said openings, a latch bar slidably guided within said casing, and means within 35 said casing for transmitting movement from said cam portion of the handle to the latch bar.
2. A drawer latch device comprising a 40 loop handle having a substantially straight cylindrical portion, an integral offset member intermediate the length of said straight portion and constituting a cam element, journal means for said handle engaging the 45 straight portion thereof at each side of said offset member, a slideable latch bolt and a pivoted member for transmitting movement from said cam element to said bolt.
3. A drawer latch comprising a casing, a 50 bolt adapted to reciprocate therein, an operating handle and a rock shaft both pivoted in the casing, a cam surface upon the handle and a cam upon the rock shaft co-acting therewith, a lift finger upon the rock shaft coating with an elongated recess in

the bolt, the parts coacting in such manner that a movement of the handle about its pivot serves to lift the bolt, the recess in the bolt being of sufficient length to permit the bolt to be lifted without transmitting motion to 55 the lift finger, and a catch associated with the latch and adapted to engage one end of the bolt, that end of the bolt being rearwardly beveled whereby contact between the catch and bevel serves to retract the bolt 60 from its catch without affecting said lift finger.

4. In combination with a drawer adapted to be drawn outwardly toward either end, a latch upon each end of the drawer, the 65 latches having outwardly swingable pull handles constructed and arranged to actuate each latch to release the drawer for movement in the direction of the pull, each latch being adapted to permit the drawer to 70 move inwardly with regard to that latch.

5. In combination with a drawer adapted to be drawn outwardly toward either end, a latch upon each end of the drawer, the latches having pull handles pivotally mounted 75 to swing outwardly and upwardly and constructed and arranged to actuate each latch to release the drawer for movement in the direction of the pull, each latch being constructed and arranged to permit the 80 drawer to move freely inwardly with regard to that latch, but to prevent it from moving outwardly with regard thereto until the latch is released.

6. A drawer latch casing comprising a 85 plate applicable to the front face of the drawer and having a pair of spaced wall members outstanding therefrom, said wall members having substantially semi-circular journal notches in their outer edges, and a 90 front member of sheet material having portions engaging said first plate and secured thereto, said front member having parts co-operating with said notches to form journals for an operating handle of continuous 95 loop formation.

Signed by me at Ilion, New York, this sixth day of August, 1920.

ENOCH OHNSTRAND.
